US00D994753S

(12) **United States Design Patent** (10) **Patent No.:** **US D994,753 S**
Wang (45) **Date of Patent:** **** Aug. 8, 2023**

(54) **INVERTED HEAD**

(71) Applicant: **PGYTECH CO., LTD.**, Kunshan (CN)

(72) Inventor: **Guangshan Wang**, Kunshan (CN)

(73) Assignee: **PGYTECH CO., LTD.**, Kunshan (CN)

(**) Term: **15 Years**

(21) Appl. No.: **29/758,174**

(22) Filed: **Nov. 12, 2020**

(30) **Foreign Application Priority Data**

Jul. 14, 2020 (CN) 202030380953.1

(51) **LOC (14) Cl.** **16-05**

(52) **U.S. Cl.**

USPC **D16/242**; D16/245

(58) **Field of Classification Search**

USPC D16/136, 211, 214, 219, 235, 236, 237, D16/241, 242, 243, 245, 250, 334; D8/352, D8/353, 354, 381, 382, 387, 394; D14/217, D14/240, 432, 447, 451

CPC ... G03B 17/561; G03B 17/563; G03B 17/566; G03B 17/565; F16M 11/041; F16M 11/06; F16M 11/043; H04N 5/2254; G02B 7/00; F16M 11/04

See application file for complete search history.

(57) **CLAIM**

The ornamental design for an inverted head as shown and described.

DESCRIPTION

FIG. 1 is a perspective view of an inverted head showing my new design;

FIG. 2 is another perspective view;

FIG. 3 is a front view;

FIG. 4 is a rear view;

FIG. 5 is a left side view;

FIG. 6 is a right side view;

FIG. 7 is a top view; and

FIG. 8 is a bottom view.

The broken lines shown on the drawings depict portions of the inverted head that form no part of the claimed design.

1 Claim, 8 Drawing Sheets
